UNITED STATES PATENT OFFICE.

GEORGE D. MOYLAN, OF PROVIDENCE, RHODE ISLAND, ASSIGNOR TO AMERICAN STANDARD WATCH CASE COMPANY, OF PROVIDENCE, RHODE ISLAND, A CORPORATION OF RHODE ISLAND.

DESIGN FOR A WATCHCASE.

Application filed February 12, 1925. Serial No. 12,360. Term of patent 7 years.

To all whom it may concern:

Be it known that I, GEORGE D. MOYLAN, a citizen of the United States, residing at Providence, in the county of Providence and State of Rhode Island, have invented a new, original, and ornamental Design for Watchcases, of which the following is a specification, reference being had to the accompanying drawing, forming part thereof.

In the said drawing:

Fig. 1 is a front plan view of a watchcase, showing my new design;

Fig. 2 is an edge view; and

Fig. 3 is a rear plan view.

I claim:

The ornamental design for a watchcase, substantially as shown.

GEORGE D. MOYLAN.
